WELL CEMENTING DEVICE

William S. Althouse, Jr., Alhambra, and Eugene Graham, Jr., Los Angeles, Calif., assignors to Baker Oil Tools, Inc., Vernon, Calif., a corporation of California

Continuation of application Serial No. 434,912, March 16, 1942. This application April 21, 1945, Serial No. 589,508

4 Claims. (Cl. 166—1)

1

The present invention relates to apparatus that is especially useful in cementing casing in well bores.

This application is a continuation of our application for "Well cementing devices," filed March 16, 1942, Serial No. 434,912, now abandoned.

It is an object of the present invention to provide an improved cementing apparatus employed in connection with the cementing of casings or other conduits in a well bore, which allows fluid to pass through it in a downward direction to a point of discharge in the casing below the apparatus, and which allows discharge of cement slurry thereafter from the casing above such point while preventing return flow of the cement slurry into the casing.

This invention has other objects which will become apparent from a consideration of several of its embodiments, shown in the drawings accompanying and forming part of the present specification. These embodiments will now be described in detail to illustrate the general principles of the invention, but it is to be understood that such detailed description is not to be taken in a limited sense, since the scope of the invention is best defined by the claims appended hereto.

Referring to the drawings:

Figure 1 is a longitudinal section through one form of an apparatus embodying the invention with some of its parts disclosed in one operative position;

Figure 2 is a view similar to Figure 1, with the parts disclosed in another operative position;

Figure 3 is a longitudinal view, partly in elevation and partly in section, of another form of the apparatus; and

Figure 4 is a view similar to Figure 3, with the parts disclosed in another operative position.

The embodiment of invention disclosed in Figures 1 and 2 includes a collar 10 forming part of a casing or similar string by being threaded or otherwise suitably coupled to adjoining casing sections 11, 12. A generally tubular body 13 is secured in the collar, as by means of threads 14 on an external body flange 15 screwed into co-operable threads on the collar positioned below its outlets or ports 16. The upper ported portion 17 of this body is generally cylindrical in shape and is spaced from the inner wall of the collar to form an annular chamber 18, in which a back pressure valve is located for preventing return flow of fluids from the exterior of the casing through the collar ports 16 and body ports or outlets 19 to the interior of the casing string. As

2

disclosed in the drawings, such back pressure valve consists of a flexible sleeve 20 having one end anchored to the body in any suitable manner, as by clamping it between the upper body portion 17 and a body head 21 threaded thereon. However, it is to be noted that the lower end of this sleeve 20 of rubber or other suitable elastic material is free to flex outwardly for the purpose of allowing cement slurry or other fluids to flow from the interior of the body through its ports 19 and the collar ports or outlets 16 to the exterior of the casing string. For the purpose of preventing leakage of fluids in both directions between the body 13 and collar 10, suitable seals 22 may be provided in the body head 21 for cooperation with the wall of the collar.

The body ports 19 are initially closed by a sleeve valve 23 positioned in the body and held across the ports 19 by frangible means, such as shear screws 24 extending into both the body and sleeve. This sleeve valve 23 has an initially open bore which will permit fluid to pass downwardly through the apparatus for ejection from the casing at a point therebelow. A valve seat 25 is also provided in the sleeve for reception of a bridging ball 26 or similar member adapted to be sent down the casing. When the bridging or tripping ball 26 engages the valve seat 25, the passage through the sleeve is closed, which allows the pressure of the fluid column above the sleeve valve 23 to be increased sufficiently for the purpose of shearing the screws 24 and moving the bridging ball 26 and sleeve valve 23 downwardly to a position in which the body ports or outlets 19 are open. The extent of this downward movement is limited by engagement of the sleeve valve with an inwardly extending body shoulder 27.

In view of the opening of the body ports 19, and the fact that the bridging ball 26 has now closed the longitudinal passage through the apparatus, the pressure of the fluid in the casing string can expand the back pressure valve 20 in an outward direction and permit the fluid to pass through the body ports 19, the annular chamber 18 and collar ports 16 to the exterior of the casing string, from where the fluids probably pass upwardly through the annulus around the casing toward the surface of the well bore.

By virtue of the apparatus described, it is possible to first circulate washing or other fluids downwardly through the entire casing string for ejection from its lower end or from a perforated section 28 positioned at a specified distance below the apparatus. After these fluids have been properly circulated or disposed around the lower or

perforated portion of the casing string, the bridging ball 26 is allowed to gravitate or is otherwise lowered through the fluid in the casing until it reaches its companion seat 25 on the sleeve valve 23. An increase in fluid pressure can then shift the sleeve 23 clear of the body ports 19 into engagement with the stop shoulder 27. Circulation may thereafter be established down through the casing for outward passage through the body and collar ports 19, 16, and for upward movement through the annulus around the casing. If the casing is to be cemented, cement slurry also follows this path of movement, with its return flow into the casing prevented by the back pressure valve 20 covering the body ports 19.

For the purpose of preventing return flow of cement slurry or other heavy fluids into the casing around its lower end or perforations positioned below the apparatus, it is preferred to incorporate a downwardly opening back pressure valve in the apparatus. In the present instance, this back pressure valve consists of a housing 29 formed as a portion of the tubular body 13 depending from the threaded flange 15 or shoulder 27. This housing contains a back pressure ball 30, preferably buoyant in mud or cement slurry, whose downward motion is limited by its engagement with spaced radial stop fingers 31 extending inwardly from the housing. These fingers may be welded to the housing or integrally formed therewith, as desired. The back pressure valve permits downward passage of fluids entirely through the body 13, but prevents return flow of fluids or upward flow of fluids through the apparatus by engaging its cooperable valve seat 32 formed in the housing portion of the body.

The inclusion of the back pressure device 30, 32 for closing the central passage of the apparatus not only prevents upward flow of fluids therethrough, but also acts as a means for enabling the casing string to be floated into the well. Any tendency for cement slurry deposited in the annulus around the casing adjacent and above the collar 10 to move downwardly around the casing string and to its interior through casing perforations would be prevented by the back pressure ball 30, since only slight upward movement of fluids in the casing immediately insures engagement of the ball with its seat 32 to close the casing against upward flow of fluids, and in so doing also prevent downward flow around the casing.

The parts within the collar are all preferably made of readily drillable material to allow their easy removal after the cement has set and hardened, and thereby leave an unobstructed bore through the casing.

In the form of invention disclosed in Figures 3 and 4, a collar 10a having lateral ports or outlets 19a is coupled to upper and lower casing sections 11a, 12a to form part of the casing string. Instead of being fixed to the collar, as in the Figures 1 and 2 embodiment, the body 13a is slidably mounted in the collar. It is provided with oppositely directed seals 35, 36 slidably sealing with the wall of the collar and initially positioned on opposite sides of the collar ports 16a by means of shear screws 37 threaded through the collar into the head 21a of the body 13a. When in this position, the body 13a engages a shoulder 38 at the upper end of the collar to relieve the shear screws 37 of upwardly directed forces imposed on the body.

The body is also provided with a ported cylin-

drical portion 11a extending upwardly from its flanged portion 15a carrying the opposed seals 35, 36 referred to. This ported portion 11a is spaced from the wall of the casing to form an annular chamber 18a in which a flexible back pressure valve 20a is positioned over the lateral body ports or outlets 19a with one end anchored to the body and the other end free to flex outwardly in allowing fluid passage from the interior of the casing string to its exterior, as described above in connection with Figures 1 and 2.

Prior to shearing of the frangible screws 37, fluids are prevented from passing from the interior of the casing and the annular chamber 18a through the collar ports 16a by the upper sealing or packing ring 35. Fluids in the annular chamber are also prevented from passing upwardly between the body 13a and collar 10a by a seal ring 22a at the upper end of the body 20a slidably engageable with the wall of the casing.

The apparatus is run in the casing with the parts positioned as disclosed in Figure 3, in which the lower two seals 35, 36 are disposed on opposite sides of the collar ports 16a to prevent passage of fluids therethrough from the interior of the casing string. When it is desired to allow fluids to so pass, a bridging ball 26a is allowed to gravitate or is pumped down the casing string until it engages a seat 25a in the body below its ports or outlets 19a, whereupon an increase in the pressure of the fluid column above the ball to a sufficient degree shears the screws 37 and forces the body 13a downwardly with respect to the collar until the lower end of its flange 15a engages a suitable stop, which may be provided by the upper end of the lower casing section 12a. When in this position, the upper seal 35 is below the collar ports 16a and the annular chamber 18a is in communication therewith, thus allowing fluids pumped down the casing to pass through the body ports 19a, urge the back pressure sleeve valve 20a laterally to one side, and pass through the chamber 18a and collar ports 16a to the exterior of the casing string. Return flow of such fluids through the collar ports 16a and body ports 19a is prevented by sealing of the flexible sleeve 20a over the ported area of the body 13a. Similarly, the uppermost seal 22a prevents leakage of such fluids in an upward direction between the body 13a and collar 10a into the casing string.

For the purpose of preventing cement slurry or other heavy fluids disposed in the annulus around the casing from lowering and passing into the casing through its lower end or perforations, an upwardly seating back pressure valve can also be incorporated in the embodiment disclosed in Figures 3 and 4. As in the other form of invention, this back pressure valve may consist of inwardly extending fingers 31a on which a back pressure ball 30a may rest in a downward direction, and a valve seat 32a in the body 13a against which the ball can seal whenever return flow of fluids in an upward direction through the casing string tends to occur from a point below the apparatus described.

It is therefore apparent that cementing apparatus has been provided which enables the casing string to be floated into the well, allows circulation to be established below the apparatus for as long as desired, and then permits the placement of cement slurry laterally through the apparatus, while preventing its return flow either through the lateral ports or through the lower portion of the casing string. In this connection, disposition of the back pressure valves in the an-

nular chambers affords them protection while lowering the casing string in the well bore.

We claim:

1. Apparatus of the character described, including a tubular member having ports and adapted to form part of a casing string, a shiftable tubular body having ports positioned within said member and provided with a medial portion of lesser external diameter than the diameter of the inner wall of said tubular member to form an annular chamber therewith, said medial portion containing said body ports, valve means within said chamber for preventing return passage of fluids from said chamber through said body ports to the interior of said body, means initially retaining said body in such position within said member as to prevent passage of fluids between said chamber and the ports of said tubular member, and means for shifting said body within said member to a position permitting passage of fluids between said chamber and tubular member ports.

2. Apparatus of the character described, including a tubular member having ports and adapted to form part of a casing string, a shiftable tubular body having ports positioned within said member and provided with a medial portion of lesser external diameter than the diameter of the inner wall of said tubular member to form an annular chamber therewith, said medial portion containing said body ports, valve means on said body within said chamber for preventing passage of fluids between said chamber and body ports, means initially retaining said body in position within said member disposed over said tubular member ports so as to prevent passage of fluids from said chamber therethrough, and means for closing the bore through said body to enable its hydraulic shifting within said member to a position permitting passage of fluids between said chamber and tubular member ports.

3. Apparatus of the character described, including a tubular member having ports and adapted to form part of a casing string, a shiftable tubular body having ports positioned within said member and provided with a medial portion of lesser external diameter than the diameter of the inner wall of said tubular member to form an

annular chamber therewith, said medial portion containing said body ports, valve means within said chamber for preventing passage of fluids from said chamber through said body ports to the body interior, means initially retaining said body in such position within said member as to be disposed over said tubular member ports to prevent passage of fluids from said chamber therethrough, means for closing the bore through said body below its ports to enable its hydraulic shifting to a position permitting passage of fluids between said chamber and tubular member ports, and a back pressure valve for preventing upward passage of fluids through said body comprising a valve seat on said body and a valve member movable upwardly to engage said seat.

4. Apparatus of the character described, including a tubular member having ports and adapted to form part of a casing string, a shiftable tubular body having ports positioned within said member and provided with a medial portion of lesser external diameter than the diameter of the inner wall of said tubular member to form an annular chamber therewith, said medial portion containing said body ports, valve means within said chamber for preventing return flow of fluids from said chamber through said body ports to the interior of said body, frangible means initially securing said body to said tubular member in a position preventing passage of fluids between said chamber and the ports of said tubular member, and means for disrupting said frangible means and shifting said body within said member to a position permitting passage of fluids between said chamber and tubular member ports.
